Alfred Goulding Inventor

UNITED STATES PATENT OFFICE.

ALFRED GOULDING, OF WORCESTER, MASSACHUSETTS, ASSIGNOR TO
EDWARD WRIGHT, OF SAME PLACE.

CUFF-HOLDER.

SPECIFICATION forming part of Letters Patent No. 427,414, dated May 6, 1890.

Application filed October 2, 1889. Serial No. 325,750. (No model.)

To all whom it may concern:

Be it known that I, ALFRED GOULDING, a citizen of the United States, residing at Worcester, in the county of Worcester and Commonwealth of Massachusetts, have invented a certain new and useful Improvement in Cuff and Garment Supporters; and I do hereby declare that the following is a full, clear, and exact description thereof, which, in connection with the drawing forming a part of this specification, will enable others skilled in the art to which my invention belongs to make and use the same.

The object of my invention is to provide a cuff and garment supporter adapted to support cuffs, shirt-sleeves, stockings, or any parts of wearing-apparel where it may be useful; and it consists of a loop struck out of sheet metal or formed of wire, having a bight at one end provided with a pin-hook, the other end of the loop having a button and hook combined.

Referring to the drawing, therein is shown a view of a supporter embodying my improvement, showing the form of the loop having a bight at one end provided with a pin, and the other the button and hook combined.

A denotes the plate; D, an oblong oval space; C C', bight at each end, and B the button and hook.

A' represents my loop formed of wire.

B' denotes the hook at one end, and D' the oblong oval space.

A² denotes the modified form of my supporter; B², the button and hook combined; C², the bight of the loop D², and E denotes the pin-hook.

Having thus described my invention, what I claim as new, and desire to secure by Letters Patent, is—

The cuff and garment supporter herein described, consisting of the loop D, having the contracted slots C and C' and provided at one end with the button B, and the pin E, pivoted to one side of the loop and adapted to swing across the contracted slot C, substantially as described.

ALFRED GOULDING.
